UNITED STATES PATENT OFFICE.

WILLIAM BODGE, OF NUTLEY, NEW JERSEY, ASSIGNOR TO THE BANNER PAPER BOX CO., OF BROOKLYN, NEW YORK, A CORPORATION OF DELAWARE.

MACHINE FOR MAKING CELL-CASES.

1,097,840.

Specification of Letters Patent.

Patented May 26, 1914.

Application filed August 5, 1912. Serial No. 713,333.

To all whom it may concern:

Be it known that I, WILLIAM BODGE, citizen of the United States, and resident of Nutley, in the county of Essex and State of 5 New Jersey, have invented certain new and useful Improvements in Machines for Making Cell-Cases, of which the following is a specification.

The invention relates to improvements in 10 machines for making cell-cases for packing eggs and other articles, and includes a feed-table adapted to receive successive sheets of card-board, means for feeding the sheets therefrom at regular intervals, means for 15 longitudinally scoring the sheets, means for longitudinally severing the sheets into strips, means for applying lines of glue or other adhesive thereto, means for collecting or laterally spacing the severed strips in 20 separated and overlapping relation with one another, and means for advancing and compressing the collected strips for the adhesive connection thereof. And the invention further includes a particular form of 25 collecting device whereby the strips are more perfectly alined with respect to one another.

In describing the invention in detail, reference is had to the accompanying drawings, 30 forming a part of this specification, wherein like characters of reference designate like parts throughout the several views, and in which:

Figure 1 is a ground plan of the machine 35 embodying the invention; Fig. 2, a sectional side elevation of the same; Fig. 3, an enlarged sectional transverse elevation of the strip collector, showing the operating mechanism thereof; Fig. 4, a detail view showing 40 the relative lateral collected position of the several strips of cardboard with the glue and score lines therein; and Fig. 5 is a perspective view showing a finished cell-case in open position.

In the drawings, numerals 1 and 2 designate respectively the front and rear frames of the machine, provided with suitable cross-braces 3 and 4. Upon one end of the frames is mounted a feed-table 5, and to the 50 opposite end thereof frame extensions 6 and 7 are secured through the cross-brace 4. Mounted in bearings upon the frames are two pairs of feeding rollers 8 and 9, and also journaled in the frames intermediate of the feeding rollers are two pairs of shafts

10 and 11, respectively carrying conventional scoring or creasing wheels 12 and slitting-wheels 13, the wheels of the respective pairs being opposed to each other for the passage of the cardboard therebetween, the creasing-wheels thereof being arranged to form a plurality of single and double score-lines longitudinally of the sheet. Mounted upon the opposite frames are a pair of brackets 14, in which are journaled the upper and lower shafts 15, carrying the feed-pulleys 16, and also supported from these brackets by the integral arms 17, is a fixed shaft 18 arranged to carry a glue-box 19, provided with a removable bottom-plate 20. Within the glue-box is journaled a shaft 21, carrying a series of glue-wheels 22, which pass through slots in the bottom plate and project below the bottom surface thereof and are provided in the usual manner with adjustable scrapers for regulating the quantity of glue thereon. Suitable feed openings or passages, not shown, are provided in the top wall of the glue-box for supplying glue thereto either continuously 70 or intermittently.

Upon the frame extensions 6 and 7, suitable bearings are provided in which are journaled two pairs of shafts 23, carrying the oppositely disposed upper and lower 85 presser-wheels 24, driven together by suitable gearing 25, which in turn is jointly driven by a gear 26, fixed upon the main shaft 27, the latter being mounted in bearings 28, supported upon the rear frame 2 and cross-brace 4. A main driving pulley 29 is fixed to the main shaft, and to the outer end of the latter is also fixed a bevel gear 30, which engages a corresponding gear 31, fixed upon the way-shaft 32, and is 90 driven therewith at a common rate of speed, the latter shaft being mounted in bearings 33, fixed upon the rear frame 2. The shaft 32 is further provided with two bevel gears 34 which engage corresponding bevel gears 100 35 and 36, loosely mounted upon studs 37, fixed to the rear frame. Fixed respectively to gears 35 and 36, and likewise loosely mounted upon the studs 37, are spur gears 38 and 39, the former, by a suitable line of 105 gearing 40, driving the feeding-rolls 8 and 9 and the scoring and slitting wheel shafts 10 and 11, and the latter, by the line of gearing 41, driving the feed-pulley shafts 15 and the glue-wheel shaft 21. The gears 110

throughout the machine are proportioned to drive the several feed rolls, scorers, slitters, glue-wheels, and presser-wheels at a common peripheral speed, corresponding with the rate of travel of the work.

For feeding the sheets of cardboard at regular intervals from the feed-table, feed-dogs 42 are provided, which pass through slots 43 in the table, the upper ends of the dogs projecting above the table to engage the rearward edge of the sheet and urge the same into the feeding-rollers 8. Each feed-dog is provided at its lower end with a hub, which slidably engages a pin 44, fixed in the bracket 45, secured upon the bottom of the feed table; a corresponding slot being formed in the foot of the bracket to slidably receive and laterally guide the upwardly extending feed-dog. For imparting movement to the dogs, the lower or hub ends thereof are pivotally connected to one end of the links 46, the opposite ends of the latter being similarly connected to the lever arms 47, fixed upon the rock-shaft 48, supported for movement in the opposite frames of the machine. Fixed upon the rock-shaft is a lever 49, pivotally connected at its lower end to one end of a connecting-rod 50, the opposite end of the latter being provided with a friction roller 51, which is engaged by a cam fixed upon the cam-shaft 52, the end of the connection-rod being slotted and loosely engaging the cam-shaft as a guide in the usual manner to receive the lateral thrust of the cam. A compression spring 47^a, fixed at its opposite ends to the brace 3 and one of the arms 47, holds the roller 51 into engagement with the cam. The cam-shaft is mounted in bearings formed on the front and rear main-frames, and motion is imparted thereto by the gear 53, which is engaged by the gear 54, fixed upon the main-shaft 27.

For making the cell-case herein shown, the sheet of cardboard is divided longitudinally by the slitting-wheels 13 into eight strips designated by A, B, C, C¹, C², C³, B¹, A¹, those having common letters being of similar widths. From the feed pulleys 16, the strips are directed to a collector 55, comprising a corresponding number of fixed supporting-plates, spaced apart from one another and carried by the side brackets 56 upon the opposite main frames of the machine. The plates loosely support the strips of cardboard, and beginning with the lowest plate, the strips are led to the successive upper plates in the order indicated by their successive reference characters, strip A being carried by the bottom plate and strip A¹ by the top plate, the relative levels of the strips being clearly shown in Fig. 4.

For leading the several strips to the collector, endless tapes or bands 57 are provided, which pass around and are driven by

the lower set of pulleys 16, and lead independently to the smaller rollers 58, severally adjustable adjacent the leading edges of the collector plates, a corresponding series of tension rollers 59 contacting the belts to afford a more perfect direction of the strips to the collector.

For transversely spacing the several strips within the collector, a series of spacing-dogs 60 and 61 are slidably mounted upon a pair of cross-shafts 62, fixed in the brackets 56, see Figs. 2 and 3. Links 63 pivotally connect the dogs to the lever-arms 64, the latter being fixed upon the rock-shafts 65, mounted in the bearings 66, and for effecting the forward and backward movement of the opposite dogs, toward and from each other, the arms are oscillated by means of the rock-shafts, and the bevel-gears 67, fixed thereon, the latter being engaged by corresponding gears 68, fixed upon the shaft 69, mounted in bearings 70. A rocking movement is imparted to this latter shaft by the lever 71, fixed thereon, and provided with a connecting-rod 72, leading to the cam-shaft 52, having a cam 73, fixed thereto; a roller 74, mounted on the connecting-rod, being held in engagement with the cam by means of a tension spring 75, which is fixed at one end to a suitable support 76, while its opposite end is connected to the lever 71. As thus connected, the cam, at each revolution, corresponding with the introduction of each successive sheet into the machine, imparts the necessary reciprocation to the dogs 60 and 61, the upper ends of which are laterally guided by and traverse the transversely-extending slots 77, extending through the several plates, and in their forward movement toward each other, engage the outer edges of the strips of cardboard and transversely move them upon the plates into suitable overlapping position with respect to each other, the engaging ends of the dogs being suitably shaped, and in the order named respectively adapted to engage strips A, B, C, C¹, and C², C³, B¹, A¹, to effect the necessary overlap thereof, as indicated in Fig. 4. For limiting the transverse movement of the strips upon the plates, stops, not shown are preferably employed, the same being adjustably fixed to the plates or other suitable support.

The several collector-plates are vertically spaced by interposed space-bars 78, and are jointly connected together and supported in connection with the brackets 56 by the upper and lower cross-bars 79 and 80, having slots 77 extending therethrough, corresponding with those of the several plates. Upon the upper cross-bars are mounted the slide-blocks 81, in which is mounted for horizontal movement the slide-bar 82, having at one end a bearing 83 in which is mounted for rocking movement a short shaft 84, upon

which is fixed a pair of feed-fingers 85, adapted to engage the rearward edges of the transversely spaced strips of cardboard and feed them forward by the movement 5 of the slide-bar 82. For this movement a link 86 is pivotally connected at its ends to a lug 87 on the slide-bar and to the arm 88, the latter being fixed upon a rock-shaft 89, carried by the bearings 90, fixed to one of 10 the cross-bars 79. Upon the outer end of rock-shaft 89 is fixed a lever 91, having a pivotal connection to the upper end of the connecting-rod 92, the lower end of which is fork shaped to engage the cam-shaft 52, 15 a cam 93, fixed on the latter, engages a roller 94 on rod 92 to effect the aforesaid movement of the slide-bar, in connection with a spring 95, the opposite ends of which are connected respectively to an extension 20 of the lever 91 and to the foot of the outer bearing 90, which action of the spring normally holds the roller 94 in contact with the cam and effects the return movement of the slide-bar. At the end of this return movement, 25 the rock-shaft 84, carried by the slide-bar, is given a slight rocking movement to tilt the fingers 85 for affording a clearance for the introduction of the strips of cardboard to the collector, the fingers extending 30 downwardly an amount sufficient only to engage their respective strips of cardboard. For this rocking movement, an upwardly-extending arm 96 having a horizontally-projecting lug 97 is fixed upon the 35 rock-shaft and engaged by a stop-bracket 98, fixed upon the adjacent cross-bar 79, the stop-bracket having at its free end a lateral projection which contacts the projecting lug 97 and serves in connection with 40 the helical spring 99 to actuate the fingers. The spring is mounted upon the end of the rock-shaft, with its outer end fixed thereto and movable therewith, while its opposite or inner end is held relatively stationary by 45 its engagement with the upper surface of the slide-bar 82. In its form and arrangement, the spring normally tends to downwardly urge the fingers fixed upon the rock-shaft, which downward movement is limited by the 50 engagement of the stops 100 and 101, respectively formed upon the bearing 83 and the hub of the adjacent relatively movable finger 85. As positioned by the stops and the action of the spring, as indicated in the 55 drawings, the lower ends of the fingers extend vertically downward for their engagement with the strips of cardboard, and, in effecting the forward movement of the latter, pass through short longitudinal clearance-slots 102, formed through the adjacent portions of the collector-plates. As fed by the finger, the transversely positioned strips of material are jointly advanced for 60 engagement by the presser-wheels 24, the leading edges of the strips being directed

thereto by suitably arranged guide-bars 103, formed on said plates or supported relative therewith.

In operation, sheets of cardboard or other suitable material, indicated in broken lines, are laid upon the feed-table 5 and adjusted against the lateral stop 104, from which point they are fed at regular intervals in spaced succession by the feed-dogs 42, which advance the work to the first pair of feeding-rolls 8, by means of which it is urged between the upper and lower scoring-wheels 12 and the slitting-wheels 13 to the second pair of feeding-rolls 9, the latter assisting in controlling the movement of the stock 70 and advancing it for engagement by the glue-wheels 22 and the upper and lower set of feeding-pulleys 16. In its travel between the scoring-wheels, single and double rows of crease lines are formed upon the stock, 75 adjacent which single lines and between which double lines, glue is applied by the glue wheels; and in its movement between the slitting-wheels, the work is longitudinally divided into strips which are severally 80 directed to the several plates of the collector 55, in the manner heretofore described, by the tapes 57, which serve to longitudinally position the same thereon. As controlled by the feed-dogs 42, sufficient space or time is 85 allowed between successive sheets to allow of transversely positioning or collecting the strips delivered upon the collector-plates and for advancing the strips thus collected for engagement by the presser-wheels 24, the 90 action of the spacing-dogs 60 and 61 and the feed-fingers 85, which respectively effect these two latter movements, being suitably timed with respect to such space, so that at each revolution of the actuating mechanism, 95 100 or cam-shaft 52, a new sheet is adapted to be presented to the presser-wheels. These latter wheels are preferably arranged upon their respective shafts to engage and compress the overlapping strips in line with the 105 glued portions thereof, and where the number of strips are materially increased for the manufacture of relatively large cell-cases, the upper wheels may be severally 110 mounted for loose rotation upon independent shafts adjustably arranged with respect to the opposite or lower set of wheels to vary the space and tension therebetween for the 115 engagement of work of varying degrees of thickness.

In the formation of the cell-case herein described, each of the several strips of material is adapted to form one or more longitudinal and transverse cell-case members, bent along the score lines substantially at 120 right angles to one another, the adjacent strips being adhesively connected together at their points of bend by the lines of glue applied adjacent said score lines, as shown in Figs. 4 and 5, in which the numerals 105 125 130

4
 designate the lateral position of the score lines and 106 the relative position of the lines of glue. These glue lines are applied on one of each of the adjoining faces of 5 the several strips in alternate relation with the score lines thereof, and, after being compressed and jointed together by the presser-wheels, the united strips are adapted to be transversely cut up into suitable lengths and 10 opened out to form the cell-case, shown in Fig. 5. In this latter view, the transverse and longitudinal members of the cell-case are designated by reference characters corresponding with those of the separate strips 15 shown in Fig. 4, from which they are formed.

As thus constructed, it will be obvious that the machine may be arranged to form cell-cases having various numbers of cells.

What I claim as my invention and desire 20 to secure by Letters Patent, is:

1. In a cell-case machine, the combination of means for feeding sheets of material at regular intervals in spaced succession, means for longitudinally severing said sheets into 25 a series of strips, means for longitudinally scoring said strips to form longitudinal and transverse cell-case members, means for applying longitudinal lines of glue to said strips adjacent said score lines, means for 30 associating said glued strips, and means for jointly compressing said glued strips for the adhesive connection thereof.

2. In a cell-case machine, the combination of means for feeding sheets of material at regular intervals in spaced succession, means for longitudinally severing said sheets into 35 a series of strips, means for longitudinally scoring said strips to form longitudinal and transverse cell-case members, means for applying longitudinal lines of glue to said strips adjacent said score lines, means for 40 associating said strips including a corresponding series of supporting-plates, means for severally directing said strips to said plates, means for transversely positioning said strips upon said plates, a series of 45 presser-wheels mounted adjacent said supporting-plates and adapted to compress said strips, and means for jointly advancing said 50 transversely-positioned strips for engagement by the presser-wheels.

3. In a cell-case machine, the combination with means for feeding sheets of material at regular intervals in spaced succession, including means for longitudinally severing, 55 scoring and gluing said sheets to form a series of strips adapted for longitudinal and transverse cell-case members, of a collector for said strips comprising a corresponding 60 series of supporting-plates provided with transverse spacing-slots, means for directing the strips to said plates, spacing-dogs mov-

able in said slots and adapted to transversely position said strips, a series of presser-wheels supported adjacent said supporting-plates and adapted to compress said strips, and feed-fingers mounted adjacent said supporting-plates and adapted to engage the rearward edges of the transversely-positioned strips and jointly advance the 65 same for engagement by the presser-wheels.

4. In a cell-case machine, the combination with means for severing a sheet of material into a series of longitudinal strips, of a collector therefor comprising a series of spaced 75 supporting-plates provided with transverse and longitudinal slots, means for directing the severed strips to said plates, spacing-dogs movable in said transverse slots and adapted to transversely position said strips, 80 and feed-fingers movable in said longitudinal slots and adapted to jointly advance the transversely-positioned strips.

5. In a cell-case machine, the combination with means for severing a sheet of material 85 into a series of longitudinal strips, of a collector therefor comprising a series of spaced supporting-plates provided with transverse and longitudinal slots, means for directing the severed strips to said plates, 90 spacing-dogs movable in said transverse slots and adapted to transversely position said strips, feed-fingers mounted for reciprocation through said longitudinal slots and adapted in their forward movement to 95 jointly advance the transversely-positioned strips, and means to deflect said feed-fingers on their return movement to allow of the direction of said strips to the collector-plates.

6. In a cell-case machine, the combination of means for forming a plurality of longitudinal score-lines on a series of strips of material, means for applying longitudinal lines of glue on one of each of the adjoining 105 faces of said strips in alternate relation with the score-lines thereof, and means for collecting and uniting said strips.

7. In a cell-case machine, the combination of means for forming a plurality of longitudinal single and double score-lines, on a series of strips of material, means for applying longitudinal lines of glue on one of each of the adjoining faces of said strips in alternate relation with the score-lines thereof and between said double score-lines, and means for collecting and uniting said strips.

Signed at New York in the county of New York and State of New York this 20th day of April A. D. 1914.
